DESIGN FOR A COMBINED FACEPLATE AND DEFLECTOR FOR A HEATER

George W. Walker, Pleasant Ridge, Mich., assignor to McAleer Manufacturing Company, Detroit, Mich., a corporation of Michigan

Application July 29, 1936, Serial No. 64,114

Term of patent 7 years

To all whom it may concern:

Be it known that I, George W. Walker, a citizen of the United States, residing in Pleasant Ridge, in the county of Oakland and State of Michigan, have invented a new, original, and ornamental Design for a Combined Faceplate and Deflectors for a Heater, of which the following is a specification, reference may be had to the accompanying drawings, forming a part of this specification, wherein:

Fig. 1 is a front elevational view of a combined faceplate and deflectors for a heater embodying my design.

Fig. 2 is a side view thereof.

I claim:

The ornamental design for a combined faceplate and deflectors for a heater substantially as shown.

GEORGE W. WALKER.
